(57) **CLAIM**

The ornamental design for an electric piano, as shown and described.

DESCRIPTION

FIG. 1 is a front perspective view of an electric piano, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 9 is another front perspective view thereof; and, FIG. 10 is an enlarged view of the portion taken at line-10 in FIG. 1.

The broken lines in the drawings illustrate the portions of the electric piano, which form no part of the claimed design. The dash-dot-dash broken lines encircling the enlarged views are for annotative purposes only and form no part of the claim thereof.

1 Claim, 10 Drawing Sheets
